UNITED STATES PATENT OFFICE.

JOHN HARRIS, OF MARQUETTE, WISCONSIN.

IMPROVED BROOM-HEAD.

Specification forming part of Letters Patent No. 59,011, dated October 23, 1866.

To all whom it may concern:

Be it known that I, JOHN HARRIS, of Marquette, in the county of Green Lake and State of Wisconsin, have invented a new and useful Improvement in Broom-Heads; and I do hereby declare that the following is a full, clear, and exact description thereof, which will enable others skilled in the art to make and use the same, reference being had to the accompanying drawings, forming part of this specification, in which—

Figure 1 is a side view of a broom-head in red lines, showing in black lines my improvement attached. Fig. 2 is an under-side view of my improvement detached from the broom-head. Fig. 3 is a detail sectional view taken through the line $\alpha\alpha$, Fig. 2.

Similar letters of reference indicate like parts.

My invention has for its object to improve the construction of my broom-head, patented May 1, 1866, and numbered 54,338; and it consists of the combination of the arms, serrated bars, and pins with each other, when said parts are constructed and combined in the manner hereinafter more fully described.

A are the arms, the upper ends of which are secured to the socket which receives and holds the upper or butt ends of the corn or other material of which the broom or brush is to be made. B are pins securely attached to or formed solidly upon the lower ends of the arms A, to receive and hold the ends of the serrated bars C, as shown in the drawings. One side of these pins, near their lower ends, is notched or grooved, as shown in Fig. 3, for the purpose hereinafter mentioned.

C are the serrated bars, which pass around the broom at about the point where the broom is usually sewed, and which said bars are bent or curved in the form which it is desired the broom should have. The ends of the bars C are perforated for the passage of the pins B, and they are also made thinner, so that when overlapped and passed over said pins the overlapped parts may be no thicker than the other parts of the said bars, as shown in Fig. 1. These bars C must be placed upon the pins B in such a way that the body of the lower bar may be on the side of the broom-head opposite to that upon which the notches are formed upon the side of the said pins B, as before described, so that the outside pressure of the broom-corn or other material of which the broom or brush is made may force the edge of the said bar into the said notches and securely hold the various parts together.

Upon the inner sides of the bars C are formed teeth, which penetrate the corn, holding it securely in its proper position and preventing it from being drawn out.

I claim as new and desire to secure by Letters Patent—

The combination of the arms A, pins B, and serrated bars C, when said arms, pins, and bars are constructed and combined substantially in the manner herein described, and for the purpose set forth.

JOHN HARRIS.
